United States Patent Office

Des. 186,976
Patented Jan. 5, 1960

186,976

DWELLING

August H. Stark, Denver, Colo.

Application September 25, 1957, Serial No. 47,863

Term of patent 7 years

(Cl. D13—1)

Des. 186,976

PAGE 2

Fig. 3

Fig. 4

Fig. 4 is a rear elevational view thereof; and

Fig. 5 is a top plan view.

I claim:

The ornamental design for a dwelling, substantially as shown.
